UNITED STATES PATENT OFFICE

2,663,115

AERATED MINNOW BUCKET

Robert G. McKissack, Bolton, Miss.

Application March 10, 1950, Serial No. 148,803

1. Claim. (Cl. 43—57)

1.

The present invention relates to an aerated minnow bucket and it consists in the combinations, constructions and arrangements of parts herein described and claimed.

Generally there is provided a minnow bucket having a valved fitting in the lower end thereof which fitting is connected by means of a pipe to a pump fitting on the lower outer side of the bucket. A novel clamp arrangement is provided for holding an air pump upon the side of the bucket and operation of the pump effects an admission of air into the lower end of the bucket to thereby aerate water which may be contained in the bucket to thereby ensure keeping alive minnows which may be placed in the water. In another form of the invention, the pump is centrally disposed in the bucket and in each case there is provided a novel perforated disc for facilitating the removal of minnows from the bucket.

It is accordingly an object of the invention to provide a device of the character set forth which is simple in construction, inexpensive to manufacture and yet which is efficient and effective in use.

Another object of the invention is the provision of a minnow bucket having novel means for aerating water which may be contained therein.

A still further object of the invention is the provision of novel means for mounting a pump upon the side of a minnow bucket of the character set forth.

Another object of the invention is the provision of a minnow bucket of the character set forth having a body formed of non-heat-conducting material.

Other and further objects of the invention will become apparent from a reading of the following specification, taken in conjunction with the drawing, in which:

Figure 1 is a central vertical sectional view, partly in elevation, of a device embodying the present invention.

Figure 2 is a plan view of Figure 1.

Figure 3 is a sectional view taken along line 3—3 of Figure 1.

Figure 4 is a sectional view taken along line 4—4 of Figure 1.

Figure 5 is a fragmentary enlarged vertical sectional view illustrating the details of a valved fitting forming a part of the invention.

Figure 6 is a vertical sectional view of a modified form the invention may assume, and

Figure 7 is a sectional view taken along line 7—7 of Figure 6.

2.

Referring more particularly to the drawing, there is shown therein a generally cylindrically shaped bucket having a body 10 and an integrally formed neck 11 constructed of thick glass or other heat resistant material. A covering 12, preferably formed of aluminum, entirely covers the bottom 13 and the sides and neck of the bucket and is provided with an inturned flange 14 at its upper end, which flange is in spaced relation to the top of the neck 11. The flange 14 is provided with a pair of diametrically opposed slots 15.

A cover 16 is provided with a plurality of perforations 17 and with a flanged portion 18 having a pair of diametrically opposed outwardly extending ears 19 and the covering 12 has affixed thereto adjacent the juncture between the body and the neck of the bucket a pair of outwardly extending bail ears 20 to which is pivotally attached a bail 21 having a handle 22.

Centrally disposed in the bottom of the container is a fitting 23 having a recess 24 in its upper end in which recess is seated a ball valve 25. A passage 26 communicates with the recess 24 and the lower end of the fitting and a pipe 27 is connected with the fitting and extends through one side of the bucket to a coupling 28. Laterally extending beneath the coupling 28 from the body of the bucket is a bracket 29 provided with a pair of diametrically opposed bayonet slots 30.

An air pump 31 having a conventional handle 32 is provided at its lower end with a pair of outstanding diametrically opposed lugs 33 and there is affixed to the covering 12 adjacent the upper end of the body and in vertical alignment with the bracket 29 a spring clip 34.

A concavo-convex shaped plate 35 having a plurality of perforations 36 therein and having its concave side uppermost, in horizontally arranged within the bucket and is of such size to allow a very small clearance between its periphery and the inner walls of the bucket. A vertically extending handle 37 is centrally affixed to the plate 35, as indicated at 38.

In operation, it will be apparent that the bucket may be filled or substantially filled with water and that thereafter live minnows 39 may be placed within the water, which water should be at a normal temperature for the proper living conditions for such minnows. The walls and neck of the bucket being of heat-resistant material will act to maintain the proper temperature of the water for considerable periods of time and it will be apparent that from time to time the handle 32 of the pump 31 may be reciprocated to

thereby force air through the valve 25 to thus allow a proper amount of oxygen to enter the bucket and become absorbed in the water for the proper preservation of the lives of the minnows 39. It will also be apparent that the pump may be mounted in the bracket 29 by engaging the lugs 33 in the bayonet slots 30 and thereafter or at the same time engaging the upper end of the pump in the spring clip 34. The pipe 27 will be then coupled with the conventional outlet pipe 40 of the pump 31 by means of the coupling 28. When it is desired to remove minnows from the bucket, it is only necessary to turn the cover 16 a quarter turn to align the legs 19 with the slots 15 and to thereafter withdraw the cover 16 from the bucket.

In the form of the invention illustrated in Figures 6 and 7 an air pump 50 is centrally mounted in the bottom 13 by means of embedding a base member 51 therein. This pump is also provided with a handle 52 which extends upwardly through the neck and which will ordinarily be enclosed within the cover 16. The pump is provided with an outlet pipe 53 which communicates directly with the interior of the bucket.

A perforated dish-shaped plate 54 is affixed to the lower ends of a pair of vertically extending shafts 55 whose upper ends are slidably mounted in a bracket 56 which is affixed to the upper portion of the pump 50.

The remainder of this form of the invention is identical with that described with regard to Figures 1 to 5, inclusive, and the operation is likewise identical with the exception that when it is desired to raise the plate 50, it is only necessary to grasp the upper ends of the shafts 55 and draw the same upwardly thereby bringing the plate 54 likewise in an upward direction so that minnows which may be in the water contained in such bucket will be drawn to the top of the bucket 40 to provide easy access thereto.

While but two forms of the invention have

been shown and described herein, it will be readily apparent to those skilled in the art that many minor forms of the invention may be made without departing from the spirit of the invention or the scope of the appended claim.

What is claimed is:

A device of the character described comprising a bucket including a cylindrical wall and a bottom wall, a valved fitting disposed in said bottom wall and communicating with the interior of the bucket, a feed pipe embedded in said bottom wall, connected at its inner end to said valved fitting and protruding from said cylindrical wall, a bracket affixed to the lower portion of the cylindrical wall and having bayonet slots therein, a spring clip affixed to the upper portion of the cylindrical wall in vertical registry with said bracket, a pump, pins affixed to the lower end of said pump and removably receivable in said bayonet slots, said pump being also removably receivable in said spring clip, a discharge pipe in the lower portion of said pump, and a coupling for interconnecting said discharge pipe with the outer end of said feed pipe.

ROBERT G. McKISSACK.
